UNITED STATES PATENT OFFICE.

HENRY A. HILLS, OF GRAND RAPIDS, MICHIGAN.

DISTILLING APPARATUS FOR VOLATILE LIQUIDS.

Application filed January 14, 1921. Serial No. 437,136.

This invention relates to distilling and purifying processes and apparatus for volatile liquids designed more particularly for use in connection with the purifying of gasoline employed for cleaning of clothing and other articles.

This application is a continuation in part of my Patent #1,372,880, dated March 29, 1921, for a "distilling and purifying apparatus for volatile liquids."

A considerable amount of cleaning fluid such as gasoline, benzine, and the like is used for cleaning, and in using large quantities of such liquids it is necessary to recover and purify the liquid so that it may be used over and over again.

The processes and apparatus heretofore used for the purification of gasoline have not been satisfactory, particularly when the gasoline or other liquid contains large quantities of impurities. In the first place, when the gasoline or other liquid contains a considerable amount of impurities, foaming takes place in the still with the result that the impurities rise to the surface of the liquid in the form of scum forming an envelope around the bubbles in the froth which is produced with the result that the impurities are mechanically carried over into the condenser. Further, with the prior forms of still, excessive quantities of steam were used and the water condensed from such steam was only partially removed from the condensed gasoline or other liquid.

One of the principal objects, therefore, of this improvement is to provide a distilling and purifying process and apparatus for volatile fluids in which foaming is eliminated.

A further object of the invention is to provide means for rapidly circulating the fluid in the still in a vertical plane to draw any scum on the surface down into the body of the fluid and mix it therewith.

An additional object of the invention is to provide a process for purifying volatile cleaning fluids by heating the fluid with steam coils and at the same time violently agitating the fluid by the direct application of steam to the fluid, by means of an aspirator, whereby a partial vacuum is created and vaporization rendered more easy.

It is also an object of the invention to provide means whereby the agitation of the fluid in the still may be continued practically as long as any fluid remains therein.

Other and further important objects of this invention will be apparent from the disclosures in the drawings and specification.

The invention (in a preferred form) is illustrated in the drawings and hereinafter more fully described.

On the drawings:

Figure 1 is an elevation of an apparatus embodying the principles of my invention and adapted to carry out my improved process with certain elements of the system shown in section.

Figure 2 is a vertical section through the steam inlet nozzle and the adjacent parts of the still.

As shown on the drawings:

The reference numeral 1 indicates as a whole the still which, as shown, consists of an upright cylinder provided with a conical cover or end 2 into which an outlet pipe 3 is connected. Said cylinder 1 is provided with a sloping bottom 4 into which a drain or outlet pipe 5 valved at 6 is provided, a valved inlet pipe 5^a being provided near the upper end of said cylinder. Mounted in the lower end of the still 1 is a steam coil 7, the inlet to which from a supply pipe 8 is controlled by a valve 9, and the outlet from which is controlled by a valve 10. Also connected into the supply pipe 8 is a valve 11 controlling the flow through a nozzle 12 within the still, which is adapted to introduce steam directly into the fluid within the still. Said nozzle 12 is shown in section in Figure 2 and consists of a reducing coupling 30 into which a short length of pipe 31 of reduced diameter is connected and threaded onto the coupling 30.

Enclosing said pipe 31 is a shell 32 to the rear end of which is connected a pipe 33. The steam passing through this nozzle is adapted to draw fluid through the pipe 33 and project it forcibly and rapidly across the still. This fluid strikes against the upper part of the inclined bottom 4 of the still and is thereby deflected upwards so that such fluid is caused to circulate in substantially a vertical plane so as to draw down the scum on the surface of the fluid and keep the latter thoroughly agitated. In view of the fact that the pipe 33 extends downwards to a point adjacent the bottom of the still, agitation of the fluid within the still will continue after the level of fluid in the still has fallen below the nozzle 110

12 and continue so long as the lower end of the pipe 33 is covered by fluid.

Mounted adjacent the still 1 is a condenser 13 comprising an upright cylinder open at its upper end and at its lower end provided with a crown sheet or plate 14 beneath which is a conical bottom 15. Connected sealingly through said crown sheet 14 are a series of upright tubes 16 which at their upper ends 10 are sealed in a plate 17 on which a conical top or cover 18 is riveted, brazed, or otherwise secured and into which said pipe 3 from the still 1 is connected. An inlet pipe 20 is connected into the lower end of the cylinder 13 to admit a flow of cooling water to surround the condenser tubes 16, and an outlet 21 is provided at a convenient point in the upper end of said cylinder 13. An outlet pipe 22 is connected to the conical bottom 15 of the condenser to receive the condensed distillate and said pipe leads into a tee into which a vent pipe 23 is connected as well as a pipe 24 leading to a separator 25 designed to separate the moisture from 15 the volatile fluid. As the separator forms no part of the present invention it need not be described in detail.

The operation is as follows:

The fluid for distillation and purification 30 is introduced into the still or cylinder 1, through the valved pipe 5, and steam is then admitted through the heating coil 7 by opening the valve 9. The utilization of the steam coil, as well as the direct introduction 35 of steam through the nozzle 12 into the fluid for heating the same, effects an economical operation of the still, for the reason that by using a combination of the dry and wet method of distillation a much less 40 volume of steam is used than in either the dry or wet methods singly. The steam coil is utilized to bring the contents of the still to the vaporization point, and after vaporization has been set up the wet steam is introduced 45 through the nozzle 12 directly into the fluid to complete the distillation, and it is obvious that by proper manipulation of the valves controlling the respective steam supplies to the still, the most efficient operation 50 for various conditions may be obtained. The horizontal nozzle 12 serves also by the introduction of steam therethrough, to set up a violent swirling motion to the contents of the still, this agitation 55 contributing largely to the effectiveness of operation as well as the efficiency or economy, as all the possible heating effect of the coils and jet is utilized. Furthermore, due to the construction of the steam inlet nozzle 12 pounding action within the still due to the steam jet is obviated, said nozzle operating 60 as an injector to draw the liquid inwardly through the pipe 33 and force the same with the jet of steam into the contents of the still. The products of distillation pass

over and into the condenser and are condensed in the upright tubes 16 and pass therefrom into the separator 25, which operates by gravity to separate the major portion of the water from the condensed fluid. 70

It will be seen that on account of the peculiar construction of the nozzle 12 of this modification of applicant's device, the liquid in the still will be aspirated or drawn into the nozzle through the pipe 33 and discharged 75 out of the end of the pipe 32 on account of the suction action created by the steam which issues from the pipe 31, inside the shell 32. In this way a continuous circulation of the liquid in the still will be maintained at all 80 times even when the level of the liquid has dropped to below the entrance of the nozzle 12 and as the pipe 33 extends to practically the bottom of the still this circulation will be maintained no matter how little liquid 85 there is in the still.

On account of the fact that the mixture of steam and liquid issuing from the nozzle 12 impinges against the inclined bottom 4 of the still the circulation of the liquid in a 90 vertical plane as before explained will be set up and maintained, and further the suction at the bottom of the still owing to the action of the pipe 33 will tend to increase and maintain this swirling action of the liquid 95 as the liquid will rise upon one side of the tank 1 and descend upon the other in order to fill the space occupied by the withdrawal of fluid immediately in the vicinity of the entrance of the pipe 33. 100

In the purification of cleaning fluid such as gasoline, one of the chief defects of the prior forms of apparatus is that foaming occurs, with the result that impurities in the fluid are carried over mechanically into the 105 condenser along with the vapor of the fluid. Now, when gasoline is heated in an ordinary still, a large quantity of impurities therein rise to the top in the form of a scum, and as ebullition proceeds the bubbles of gasoline vapor forcing their way to the surface through the layer of scum become enveloped thereby so that a froth is formed which fills up until the entire vapor space of the still is filled with a foam or froth which is finally carried over mechanically into the condenser. Now this froth contains a large quantity of the original impurities so that the final product is nearly as dirty as the original product. It will be seen that in this 110 invention the production of froth is entirely avoided on account of the violent stirring of the liquid in the still that is produced by the particular nozzle of applicant. Especially due to the circulation of the contents of the 115 still in a vertical plane any scum which rises to the surface of the fluid is again drawn down into the body of the fluid which is chiefly due to the suction action of the pipe 33 and this scum is thereby mixed again 120

with the original fluid so that there is no such accumulation of dirt at the surface of the liquid as will enable a froth to form.

I am aware that the details of construction 5 may be varied through a wide range without departing from the principles of this invention and I therefore do not purpose limiting the patent granted otherwise than necessitated by the prior art.

10 I claim as my invention:

1. In a still for purifying cleansing liquids, a nozzle horizontally disposed adjacent the bottom of the still adapted to inject steam into the liquid therein, a sleeve 15 rounding said nozzle and spaced therefrom to provide an annular chamber therearound, a pipe attached to the rear of said chamber and extending to the bottom of the still, for supplying fluid through the chamber simultaneously with the exhaust from the nozzle,

20 and means for deflecting said injected steam and fluid upward.

2. In a still for purifying cleansing liquids, a bottom therefor inclined downwardly from one side to the other, a nozzle 25 horizontally disposed adjacent said bottom and adapted to inject steam into the liquid in said still and against said inclined bottom, a sleeve surrounding said nozzle and spaced therefrom to provide an annular 30 chamber therearound, and a pipe attached to the rear of said chamber and extending downward to near the still bottom at its lowermost point for supplying fluid through the chamber simultaneously with the exhaust 35 from the nozzle.

In testimony whereof I have hereunto subscribed my name.

HENRY A. HILLS.
